CENTER MARK TRANSFERRING DEVICE
Peter J. Fleck, 921 NE. 17th St., Auburn, Wash.
Filed Sept. 20, 1963, Ser. No. 310,364
4 Claims. (Cl. 33—189)

My invention relates to a center mark transferring device.

An object of my invention is to provide a simple and efficient device which can be used to transfer a center mark on one part or piece to a corresponding position on another part or piece.

Another object is to provide a center mark transferring device which is well adapted for multiple use and which saves much time and labor and insures greater accuracy and minimizes the danger of error in instances where a plurality of my devices are used, to transfer to a second part or piece, an identical marking of a plurality or relatively large number of points or centers which have already been established, marked or laid out on a first part or piece.

Another object is to provide a center mark transferring device which is particularly well adapted for use in connection with magnetic material and which utilizes a permanent magnet to hold it immovable and in a predetermined location on a part or piece of magnetic material.

Another object is to provide a center mark transferring device comprising a body member formed of at least two layers of material of substantial thickness rigidly secured together and having two opposed, substantially parallel, spaced apart end surfaces, one of said layers being of non-magnetic material and the material which forms the other layer being permanently magnetized, said two layers having a continuous passageway extending entirely through them perpendicularly to their flat end surfaces, and said passageway having therein a movable centering pin of tool steel or like magnetic material which terminates in two coaxial conically pointed ends and which is of an over-all length at least slightly greater than the total thickness of the two secured together layers.

Other objects of my invention will be apparent from the following description and accompanying drawings.

In the drawings FIGURE 1 is an end view of a center mark transferring device constructed in accordance with my invention.

FIG. 2 is a sectional view of the same taken substantially on broken line 2—2 of FIG. 1, parts being shown in elevation.

FIG. 3 is an elevational view, with a part in section, illustrating one typical use of a plurality of my devices.

FIG. 4 is a sectional view, with parts in elevation, showing a center mark transferring device of modified form.

FIG. 5 is a sectional view, with parts in elevation, showing a modification of my invention by which the center of a hole in one piece of material can be accurately marked on another piece of material.

Like reference numerals refer to like parts throughout the several views.

The center mark transferring device shown in FIGS. 1, 2 and 3 comprises a main body member 10 of non-magnetic material, such as aluminum, having one plane flat side 11 and having in its other side a relatively large recess 12 wherein a permanent magnet 13 is disposed and fixedly and non-removably secured. For instance the magnet 13 may be pressed into the recess 12. Preferably the magnet 13 protrudes a short distance beyond the adjacent end of the body member 10 and terminates in a plane flat end or face 15 which is substantially parallel to the plane flat end or face of the main body member 10. Two registering cylindrical bores 16 and 17 are provided in the body member 10 and magnet 13 respectively

2

and cooperate in forming a passageway which extends entirely through the device between the two flat sides or faces 11 and 15 and has its axis perpendicular to said two flat sides 11 and 15. Preferably the bore 16 in the body member 10 is reamed to a true and accurate and smooth cylindrical shape to provide a close working fit for a centering pin 20 of magnetizable material which is longitudinally movably disposed within the passageway formed by the two bores 16 and 17 and is accurately sized and finished so that it has a close tolerance fit in the bore 16 and is freely movable longitudinally a limited amount. The centering pin 20 is provided with two conically shaped pointed ends 21 and 22 and the over-all length of said centering pin on an axial line from tip to tip of said pointed ends is at least slightly greater than the total thickness of the body member 10 and magnet 13 measured between the two flat end surfaces 11 and 15. A recess 23 is provided in the centering pin 20 adjacent an end of said pin. This recess 23, as herein illustrated, is 10 in the form of a flattened area on a side of the pin 20 but it can be in the form of a groove which encircles said pin. A limit pin 24 extends radially into the body member 10 and has its inner end portion positioned within the recess 23 to limit longitudinal movement of the pin 20 15 and prevent said pin 20 from being pushed out of the passageways 16 and 17. Preferably the limit pin 24 is a non-removable type of holding device known to the trade as a "U-DRIVE" screw, which can be pressed into the body member 10. However it will be understood that 20 an ordinary set screw can be threaded into the body member 10 and used as a limit pin.

FIG. 3 illustrates one typical use of my center mark transferring device in connection with a conventional mold set which comprises two mold members 25 and 26, 35 at least one of which is made of magnetizable material. In conventional mold sets of this type one of the mold members, such as member 25, is ordinarily provided with rigidly attached perpendicular guide posts 27 and the other mold member 26 is slidable guided on the posts 27 for movement toward and away from the mold member 25. In forming mold cavities in the two members of mold sets of this type it is usually necessary to work from corresponding centers in said two mold members 25 and 26. Ordinarily the centers to be used in forming the cavities in the lower mold member 25 are first located and marked with shallow punch marks as indicated at 40 28. Then, in accordance with common practice, corresponding points must be located by measurements on the other mold member 26.

Although FIG. 3 is illustrative of a set up in which only three points 28, which have been located and marked on mold part 25 must be marked in corresponding locations on mold part 26, it will be understood that usually a large number of points marked on one mold part must be accurately located and marked on the other mold part and that laying out or marking these points on the second mold part must be accurately done and is time consuming and that there is always a substantial possibility of error. My center mark transferring devices save time and labor and substantially eliminate the possibility of error in transferring the center marks from one mold member to another when used as follows. After centers have been correctly located and marked by the punch marks 28 on the first mold member 25 one of my devices is positioned over each center with the tip 22 of the centering pin 20 in the punch mark 28 and the flat surface 15 of the magnet 13 resting on the member 25. The attraction exerted by magnet 13 on the centering pin 20 always yieldingly urges this pin 20 into a position in which the tip 22 thereof protrudes beyond the plane of the magnet end 15 so that said tip 22 can

readily be positioned in a punch mark 28. When the device is thus positioned the pull of the magnet 13 will draw the device firmly down onto the member 25, which is of magnetic material, and will cause the upper conical point 21 of the pin 20 to protrude above the plane of the surface 11. After one of the center mark transferring devices has been correctly positioned over each marked center 28 of the mold member 25 the other mold member 26, guided on the posts 27, is pressed against the points 21 of the pins 20 with enough force to mark on the member 26 a set of centers which are accurately aligned with, and correspond in relative positioning and spacing to, the marks 28 on the member 25. The force exerted by the magnet 13 helps to properly seat the end 22 of the pin 20 in a conical punch mark 28 and by so doing properly aligns the axis of the pin 20 with the punch mark and holds the device against displacement on the member 25 so that an accurately aligned mark on the member 26 can be made on the other mold member 26. All pins 20 are of accurately standardized length.

Obviously the use of my device is not confined to mold members but it can be used in many other instances to transfer center marks from one piece to another.

In the modified form of my invention shown in FIG. 4 the magnet 35 is not an inserted part but is a flat plate rigidly attached to another flat plate 36 of non-magnetic material. The two plates 35 and 36 have two opposed parallel flat surfaces 37 and 38 respectively and have a passageway 39 extending therethrough perpendicular to the flat end surfaces 37 and 38. The passageway 39 receives and supports a centering pin 20 identical with the centering pin shown in FIGS. 1 to 3. The centering device shown in FIG. 4 is used in the same manner as the centering device shown in FIGS. 1 to 3.

In the modified form of my invention shown in FIG. 5 the main body member 10 and limit pin 24 are the same as those shown in FIGS. 1, 2 and 3. An inserted magnet 13' in said member 10 has a bore 17' which is coaxial with but of substantially larger diameter than the bore 16 in the main body member 10. A centering pin 40 of magnetizable material having a conically pointed upper end 41 and having a side notch 42 to receive the end portion of the limit pin 24 is longitudinally movably disposed in the bore 16. The lower end of the centering pin 40 is enlarged to form a head 43 of suitable diameter to fit closely but movably in the enlarged bore 17' of the magnet 13'. The head 43 terminates in a symmetrical lower end portion 44 of conical shape and this end portion 44 is normally caused by the magnetic force to protrude from the lower end of the magnet 13'. When the device of FIG. 5 is positioned over a hole 45 in a member 46 of magnetizable material the conical part 44 of the head 43 will be centered in said hole 45 and a mark coincident with the axis of the hole 45 can be made on any piece of material which is pressed against the conical tip 41 of the pin 40. Obviously if there are a plurality of holes in the member 46 and one of my center marking devices is used in connection with each of said holes, then centers truly aligned with the axes of all of said holes can be simultaneously marked on another member by pressing it against the points 41 of centering pins 40.

The foregoing description and accompanying drawings clearly disclose preferred embodiments of my invention but it will be understood that changes may be made within the scope of the following claims.

I claim:

1. A center mark transferring device comprising a member formed at least partly of permanently magnetized material, said member having two substantially parallel spaced apart flat faces and having a straight tubular passageway perpendicular to said flat faces and extending between said flat faces, the magnetic force of said per-

manently magnetized material being of maximum strength at one of said flat faces; and a centering pin of magnetizable material longitudinally movably supported and guided in said passageway, said centering pin having two coaxial conically pointed ends and the over-all length of said centering pin being greater than the thickness of said member between said two flat faces, said pin being urged by the magnetic force of said permanently magnetized material into a position in which a pointed end of the pin protrudes beyond the flat face at which the magnetic force is of maximum strength.

2. A center mark transferring device comprising a layer of non-magnetic material of substantial thickness; a layer of permanently magnetized material of substantial thickness rigid with said non-magnetic layer, said two layers having two opposed spaced apart flat faces and having a straight tubular passageway perpendicular to the flat face of said layer of permanently magnetized material and extending through said two layers of material between said flat faces; and a centering pin of magnetizable material longitudinally movably supported in said passageway, said centering pin having two coaxial pointed ends and the over-all length of said centering pin being at least slightly greater than the thickness of said two layers of material between said two flat faces and said magnetized layer normally urging said pin into a position in which a pointed end of the pin protrudes beyond the plane of said flat face of said magnetized layer.

3. The apparatus as claimed in claim 2 in which devices rigid with one of said layers of material are positioned to engage with and limit longitudinal movement of said centering pin.

4. A center mark transferring device comprising a body member of non-magnetic material having two parallel flat ends and having a recess extending from one end thereof inwardly and an opening of smaller diameter than said recess extending from the bottom of said recess to the other end thereof; an insert of magnetized material disposed within said recess and rigid with said body member, said insert having a flat face positioned a short distance outwardly from the plane of the adjacent flat end of the body member, said insert having therein an opening registering with the opening in said body member and cooperating with said opening in said body member in forming a continuous straight passageway extending entirely through the body member and insert; and a centering pin of magnetizable material supported and guided in said passageway for longitudinal movement, said centering pin having two coaxial pointed ends and the over-all length of said centering pin being greater than the over-all thickness of the body member and insert, whereby one pointed end of the centering pin can protrude beyond the flat face of the insert and the other pointed end of the centering pin can protrude beyond the flat end of the body member remote from the insert.
